(57) **CLAIM**

The ornamental design for a mobile phone shell, as shown and described.

DESCRIPTION

FIG. 1 is a front perspective view of a mobile phone shell, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a front perspective view of the mobile phone shell in an opened state; and,

FIG. 12 is a rear perspective view of the mobile phone shell in an opened state.

The dash-dash broken lines in the figures are for the purposes of illustrating portions of the mobile phone shell which form no part of the claimed design. The dot-dash broken line circles in FIGS. 1, 9, and 10 are included for the purpose of delineating the partial enlarged views and form no part of the claimed design.
